Attorney.

UNITED STATES PATENT OFFICE.

MIRIAM NATHAN, OF NEW YORK, N. Y.

DESIGN FOR A TEXTILE FABRIC.

52,287.

Specification for Design.

Patented Aug. 20, 1918.

Application filed June 8, 1918. Serial No. 239,054. Term of patent 3½ years.

To all whom it may concern:

Be it known that I, MIRIAM NATHAN, a citizen of the United States, residing at New York, in the county and State of New York, have invented a new, original, and ornamental Design for a Textile Fabric, of which the following is a specification, reference being had to the accompanying drawing, forming part thereof.

The figure is a plan view of a portion of a textile fabric illustrating my new design.

I claim:

The ornamental design for a textile fabric, as shown.

MIRIAM NATHAN.
